(57) **ABSTRACT**

A CPR chest compression device with a cooling exhaust flow path configured to direct cooling air flow through the device. A CPR chest compression device with a battery retainer interoperable with the control system to provide for controlled shut-down when an operator attempts to remove the battery during operation.

Related Applications

This application is a U.S. National Stage Entry of International Application No. PCT/US2019/024927, entitled “CPR COMPRESSION DEVICE WITH COOLING SYSTEM AND BATTERY REMOVAL DETECTION,” and filed Mar. 29, 2019, which claims the benefit and priority of U.S. Non-Provisional Application No. 15/942,309, entitled “CPR COMPRESSION DEVICE WITH COOLING SYSTEM AND BATTERY REMOVAL DETECTION,” and filed Mar. 30, 2018.

This application is also a continuation-in-part of U.S. Non-Provisional application Ser. No. 15/942,309, entitled “CPR COMPRESSION DEVICE WITH COOLING SYSTEM AND BATTERY REMOVAL DETECTION,” and filed Mar. 30, 2018. All above-identified applications are hereby incorporated by reference in their entireties.

FIELD

The present disclosure relates to the field of CPR chest compression devices.

BACKGROUND

Cardiopulmonary resuscitation (CPR) is a well-known and valuable method of first aid used to resuscitate people who have suffered from cardiac arrest. CPR requires repetitive chest compressions to squeeze the heart and the thoracic cavity to pump blood through the body. In efforts to provide better blood flow and increase the effectiveness of bystander resuscitation efforts, various mechanical devices have been proposed for performing CPR. In one type of mechanical chest compression device, a belt is placed around the patient’s chest and the belt is used to effect chest compressions, for example our commercial device, sold under the trademark AUTOPULSE®.

These devices have proven to be valuable alternatives to manual CPR. The devices provide chest compressions at resuscitative rates and depths. A resuscitative rate may be any rate of compressions considered effective to induce blood flow in a cardiac arrest victim, typically 60 to 120 compressions per minute (the CPR Guidelines 2015 recommends 100 to 120 compressions per minute in adult victims), and a resuscitative depth may be any depth considered effective to induce blood flow, and typically 1.5 to 2.5 inches (the CPR Guidelines 2015 recommends 2 to 2.4 inches per compression in adults).

SUMMARY

It would be advantageous in a CPR chest compression device to provide for cooling of heat generating components such as the motor and the battery. The motor and battery both generate heat during operation the chest compression device, and it is advantageous to avoid excessive heating. The devices and methods described below provide for improved cooling in a CPR chest compression device. The chest compression device may include a housing configuration with baffles establishing a flow path over the battery and motor of the device, and exhaust fans which draw air from the vicinity of the motor to direct exhaust flow out of exhaust ports on the side of the housing.

On another front, it is advantageous to record operating data from the CPR chest compression device during use. This data may include the operating start times and stop times, battery life data or other battery metrics, compression rates, compression depths, total compressions applied and compressions pauses used, and other quality metrics. This data may be used for diagnosis of the patient, analysis of the effectiveness of compressions, and analysis of the operations of the chest compression device itself. Sudden loss of power to the control system can disrupt data collection, and result in loss of data collected, and it would be advantageous to prevent removal of the battery in order to replace it from causing loss of data.

The CPR chest compression device can include a compression device housing which houses various components including a drive spool and motor for rotating the drive spool, a motor with its motor housing, a fan disposed within the compression device housing, and a pathway for cooling airflow which includes an intake aperture and an exhaust aperture. The fan is disposed within the compression device housing, proximate a second end of the motor housing, between the second end of the motor housing and the exhaust aperture of the compression device housing, arranged to draw air from the second end of the motor housing and force air out the exhaust aperture of the compression device housing. The enclosure formed by the compression device housing may be configured with internal surfaces to direct air drawn by the fan through the compression device intake aperture, to an aperture in the motor housing.

The devices and methods described below provide for controlled shut-down of the CPR chest compression device when an operator attempts to remove the battery during operation, as might happen when the control system determines that the battery in use is nearing depletion or exhaustion, or the operator determines that a battery in use is nearing depletion or exhaustion. This is accomplished with a battery retainer mechanism, e.g., a latching mechanism, holding the battery in place, imposing an inherent short delay in removal, along with a detection mechanism which detects an attempt during the beginning of the removal process, with the control system programmed to recognize detection of a removal and operate to save data to a storage device, which may comprise fixed media, storage media, removable media, non-removable media, or memory including non-volatile memory and operate the system to ensure that the data is recoverable.

The CPR chest compression device can include a mechanism for detecting an attempt to remove its battery, and placing the control system in a safe condition, including completing the writing of collected patient and/or device data to a storage device, which may comprise fixed media, storage media, removable media, non-removable media, or memory including non-volatile memory, and/or ceasing further writing, before the battery is removed by a user. In a system where the control system is configured to control the chest compression device and write patient data and/or device data detected by sensors associated with the system to a storage device, a battery retainer may be configured to provide a signal to the control system indicating an attempt to remove the battery, and the control system can be correspondingly programmed to receive the signal and save data and cease writing data within a predetermined period which is shorter than the time required to complete battery removal. This system comprises a mechanical retaining structure for retaining the battery, configured to secure the battery to the chest compression device. The battery retainer

may be operable by the user to release the battery from the chest compression device, wherein operation by the user to release the battery from the chest compression device requires moving the mechanical retaining structure through a range of motion, including an initial range of motion less than a full range of motion required to release the battery from the chest compression device. A sensor for detecting a motion of the mechanical retaining structure at a point in the range of motion prior to release of the battery (an initial range of motion), and the sensor operable to generate a signal indicative of said motion and transmit said signal to the control system. The control system is operable to receive the signal indicative of the motion and is programmed to cease writing patient data and/or device data to the storage device upon receiving the signal indicative of said motion. The control system may be operable to (1) complete any writing in progress when the signal indicative of the motion is received, and (2) cease further writing of patient data and/or device data to the storage device upon receiving the signal indicative of the motion, within the predetermined time period, and the battery retainer is further configured such that the time required for a user to move the mechanical retaining structure from the initial range of motion through the full range of motion exceeds the predetermined time period.

Thus, according to one aspect, a system for performing chest compressions on a patient is provided, said system comprising:

a motor, said motor having a motor shaft, said motor having a motor housing, a first end and a second end, with the motor shaft disposed at the second end, and a first aperture in the motor housing proximate the first end, and a second aperture in the motor housing proximate the second end;

a compression device housing for housing the motor, said compression device housing configured to support or be positioned next to the patient during operation of the CPR compression device, said compression device housing forming an enclosure substantially enclosing the motor and having an intake aperture for intake of cooling airflow and an exhaust aperture for exhaust of cooling airflow; and

a first fan disposed within the compression device housing, said fan disposed proximate the motor, between the motor housing and one of the intake aperture or the exhaust aperture of the compression device housing, arranged to draw or force air through the motor housing and/or draw or force air out the exhaust aperture of the compression device housing.

The system may further comprise a drive spool. The motor shaft may be operably connected to the drive spool for rotating the drive spool. The drive spool may be configured for attachment to a belt for compressing the chest of the patient. The compression device housing may house the motor housing and/or the drive spool. The fan may be disposed proximate the second end of the motor housing. The fan may be between the second end of the motor housing and the exhaust aperture of the compression device housing. The fan may be arranged to draw air from the second end of the motor housing and force air out the exhaust aperture of the compression device housing. The intake aperture may be disposed in a superior portion of the compression device housing. The intake aperture may be on a first superior side of the compression device housing. The exhaust aperture may be disposed in a first lateral portion of the compression device housing. The exhaust aperture may be disposed on a first lateral side of the compression device

housing. The compression device housing may be configured with baffles to direct air, driven or drawn by the first fan, into the first aperture in the motor housing proximate the first end of the motor. The exhaust aperture in the motor housing may be disposed on the first lateral side of the compression device housing, inferior to the intake aperture. The intake aperture may be disposed in a lateral portion of the compression device housing. The intake aperture may be disposed on a first lateral side of the compression device housing. The exhaust aperture may be disposed in a lateral portion of the compression device housing. The exhaust aperture may be disposed on a second lateral side of the compression device housing. The compression device housing may be configured with one or more baffles or walls to direct air, driven or drawn by the first fan, into the first aperture in the motor housing proximate the first end. The second aperture in the motor housing may be disposed on a side of the compression device housing opposite the intake aperture. The first fan may be operable as an intake fan to force air through the motor housing. The system may further comprise a second fan operable as an exhaust fan to draw air from the motor enclosure and force air from the enclosure and out the exhaust aperture of the compression device housing. The first fan may be operable as an intake fan to force air through the motor housing. The system may further comprise a second fan operable as an exhaust fan to draw air from the motor enclosure through the motor housing and force air from the motor enclosure and out the exhaust aperture of the compression device housing. The system may further comprise a gearbox or transmission proximate to the motor housing. The compression device housing may be configured with one or more baffles or walls to direct air, driven or drawn by the first fan, over or through the gearbox or transmission. The one or more baffles or walls may comprise one or more apertures which are sized to allow for equal or different airflow between the motor and gearbox or transmission. The housing may further comprise seals or baffles to prevent or inhibit air flow from bypassing a flow path through the motor housing. The enclosure formed by the compression device housing may be configured with internal surfaces to direct air drawn by the fan through the intake aperture, to the first aperture in the motor housing. The enclosure formed by the compression device housing may be further configured with internal surfaces to direct air drawn by the fan from the second aperture in the motor housing, through the fan, and out the exhaust aperture. The compression device housing may be further configured with a battery compartment configured to hold a battery for powering the motor. The battery compartment may be disposed in between the intake aperture and the first end of the motor. The battery compartment may have an internal surface configured to direct air drawn by the fan through the intake aperture over or through the battery. The battery compartment internal surface may be further configured to prevent air drawn by the fan through the intake aperture from flowing through the battery compartment along pathways not at least partially defined by a battery configured for insertion into the battery compartment. The motor may be a brushed DC motor. The motor may have a commutator and brush assembly disposed at the first end. The system may further comprise a hydrophobic mesh covering the exhaust aperture. The system may further comprise a hydrophobic mesh covering the intake aperture. The intake aperture may be in a location in the compression device housing that shields the intake aperture from being blocked or obstructed. The location of the intake aperture may be recessed relative to a posterior surface of the chest compression device

housing. The system may further comprise a baffle within the compression device housing. The baffle may separate the battery compartment from the first end of the motor. The baffle may also be disposed between the intake aperture of the compression device housing and the first end of the motor. The baffle may have an aperture communicating from the battery compartment to the first end of the motor. There may be a hydrophobic mesh covering the aperture of the baffle.

According to another aspect, a system for performing chest compressions on a patient is provided, said system comprising:

a motor, said motor having a motor shaft, said motor characterized by a motor housing, a first end and a second end, and the motor shaft disposed at the second end, and a first aperture in the motor housing proximate the first end, and a second aperture in the motor housing proximate the second end;

a compression device housing for housing the motor, said compression device housing configured to support or be positioned next to the patient during operation of the CPR compression device, said compression device housing forming an enclosure substantially enclosing the motor and having an intake aperture for intake of cooling airflow and an exhaust aperture for exhaust of cooling airflow;

a first fan disposed within the compression device housing, said fan disposed proximate the motor, between the motor housing and one of the intake aperture or the exhaust aperture of the compression device housing, arranged to draw or force air through the motor housing and/or draw or force air out the exhaust aperture of the compression device housing;

a baffle disposed within the compression device housing, between the intake aperture of the compression device housing and the first end of the motor housing, said baffle configured to direct air drawn by the fan through the intake aperture of the compression device housing to the first aperture of the motor housing.

The system may further comprise a drive spool. The motor shaft may be operably connected to the drive spool for rotating the drive spool. The drive spool may be configured for attachment to a belt for compressing the chest of the patient. The compression device housing may house the motor housing and/or the drive spool. The fan may be disposed proximate the second end of the motor housing. The fan may be between the second end of the motor housing and the exhaust aperture of the compression device housing. The fan may be arranged to draw air from the second end of the motor housing and force air out the exhaust aperture of the compression device housing. The intake aperture may be disposed in a superior portion of the compression device housing. The intake aperture may be disposed on a first superior side of the compression device housing. The exhaust aperture may be disposed in a first lateral portion of the compression device housing. The exhaust aperture may be disposed on a first lateral side of the compression device housing. The compression device housing may be configured with baffles to direct air, driven or drawn by the first fan, into the first aperture in the motor housing proximate the first end of the motor. The exhaust aperture in the motor housing may be disposed on the first lateral side of the compression device housing, inferior to the intake aperture. The intake aperture may be disposed in a lateral portion of the compression device housing. The intake aperture may be disposed on a first lateral side of the compression device housing. The exhaust aperture may be

disposed in a lateral portion of the compression device housing. The exhaust aperture may be disposed on a second lateral side of the compression device housing. The baffle may be configured to direct air, driven or drawn by the first fan, into the first aperture in the motor housing proximate the first end. The second aperture in the motor housing may be disposed on a side of the compression device housing opposite the intake aperture. The first fan may be operable as an intake fan to force air through the motor housing. The system may further comprise a second fan operable as an exhaust fan to draw air from the motor enclosure and force air from the enclosure and out the exhaust aperture of the compression device housing. The first fan may be operable as an intake fan to force air through the motor housing. The system may further comprise a second fan operable as an exhaust fan to draw air from the motor enclosure through the motor housing and force air from the motor enclosure and out the exhaust aperture of the compression device housing. The housing may further comprise seals or baffles to prevent or inhibit air flow from bypassing a flow path through the motor housing. The system may further comprise a gearbox or transmission proximate to the motor housing. The compression device housing may be configured with one or more baffles or walls to direct air, driven or drawn by the first fan, over or through the gearbox or transmission. The one or more baffles or walls comprise one or more apertures which are sized to allow for equal or different airflow between the motor and gearbox or transmission. The housing may further comprise seals or baffles to prevent or inhibit air flow from bypassing a flow path through the motor housing. The system may further comprise a battery compartment for holding a battery to power the motor. The battery compartment may be disposed within the compression device housing proximate the first end of the motor. The battery compartment may be disposed between the first end of the motor and the intake aperture of the compression device housing. The system may further comprise a battery configured to be secured within the battery compartment. The battery may be configured relative to the battery compartment so as to define a flow path for air from the intake aperture of the compression device housing to the first aperture of the motor housing. The battery may be sized relative to the battery compartment so that the flow path is defined between a surface of the battery and an internal surface of the battery compartment. The battery may be configured with a channel running through the battery, and said channel may define the flow path. The motor may be a brushed DC motor, with a commutator and brush assembly disposed at the first end. The system may further comprise a hydrophobic mesh covering the exhaust aperture. The system may further comprise a hydrophobic mesh covering the intake aperture. The intake aperture may be in a location in the compression device housing that shields the intake aperture from being blocked or obstructed. The location of the intake aperture may be recessed relative to a posterior surface of the chest compression device housing. The system may further comprise a second baffle within the compression device housing. The second baffle may separate the battery compartment from the first end of the motor. The second baffle may also be disposed between the intake aperture of the compression device housing and the first end of the motor. The second baffle may have an aperture communicating from the battery compartment to the first end of the motor. The system may further comprise a hydrophobic mesh covering the aperture of the second baffle.

According to another aspect, a system for performing chest compressions on a patient is provided, said system comprising:

a motor, said motor having a motor shaft, said motor having a motor housing, a first end and a second end, the motor shaft may be disposed at the second end, and a first aperture in the motor housing proximate the first end, and a second aperture in the motor housing proximate the second end;

a compression device housing for housing the motor, said compression device housing may be configured to support or be positioned next to the patient during operation of the CPR compression device, said compression device housing forming an enclosure substantially enclosing the motor and having an intake aperture for intake of cooling airflow and an exhaust aperture for exhaust of cooling airflow; and

a first fan disposed within the compression device housing, said fan disposed proximate the motor, between the motor housing and one of the intake aperture or the exhaust aperture of the compression device housing, arranged to draw or force air through the motor housing and/or draw or force air out the exhaust aperture of the compression device housing; wherein

the intake aperture is disposed in a lateral portion of the compression device housing, on a first lateral side of the compression device housing, and the exhaust aperture is disposed in a lateral portion of the compression device housing, on a second lateral side of the compression device housing, and the compression device housing is configured with one or more baffles or walls to direct air, driven or drawn by the first fan, into the first aperture in the motor housing proximate the first end.

The system may further comprise one or more drive spools. The motor shaft may be operably connected to a drive spool for rotating the drive spool. The drive spool may be configured for attachment to a belt for compressing the chest of the patient. The compression device housing may house the motor housing. The second aperture in the motor housing may be disposed on a side of the compression device housing opposite the intake aperture. The first fan may be operable as an intake fan to force air through the motor housing. The system may further comprise a second fan operable as an exhaust fan to draw air from the motor housing or from the motor enclosure through the motor housing and force air from the motor housing or from the motor enclosure and out the exhaust aperture of the compression device housing. The first fan may be operable as an intake fan to force air through the motor housing. The system may further comprise a second fan operable as an exhaust fan to draw air from the motor enclosure through the motor housing and force air from the motor enclosure and out the exhaust aperture of the compression device housing. The system may further comprise a gearbox or transmission proximate to the motor housing. The compression device housing may be configured with one or more baffles or walls to direct air, driven or drawn by the first fan, over or through the gearbox or transmission. The one or more baffles or walls may comprise one or more apertures which are sized to allow for equal or different airflow between the motor and gearbox or transmission. The housing may further comprise seals or baffles to prevent or inhibit air flow from bypassing a flow path through the motor housing. The enclosure formed by the compression device housing may be configured with internal surfaces to direct air drawn by the fan through the intake aperture, to the first aperture in the motor housing. The enclosure formed by the compression device housing may be further configured with internal surfaces to direct air

drawn by the fan from the second aperture in the motor housing, through the fan, and out the exhaust aperture. The compression device housing may be further configured with a battery compartment configured to hold a battery for powering the motor. The battery compartment may be disposed in between the intake aperture and the first end of the motor. The battery compartment may have an internal surface configured to direct air drawn by the fan through the intake aperture over or through the battery. The battery compartment internal surface may be further configured to prevent air drawn by the fan through the intake aperture from flowing through the battery compartment along pathways not at least partially defined by a battery configured for insertion into the battery compartment. The motor may be a brushed DC motor. The motor may have a commutator and brush assembly disposed at the first end. The system may further comprise a hydrophobic mesh covering the exhaust aperture. The system may further comprise a hydrophobic mesh covering the intake aperture. The intake aperture may be in a location in the compression device housing that shields the intake aperture from being blocked or obstructed. The location of the intake aperture may be recessed relative to a posterior surface of the chest compression device housing. The system may further comprise a baffle within the compression device housing. The baffle may separate the battery compartment from the first end of the motor. The baffle may also be disposed between the intake aperture of the compression device housing and the first end of the motor. The baffle may have an aperture communicating from the battery compartment to the first end of the motor. There may be a hydrophobic mesh covering the aperture of the baffle.

According to another aspect, a system for performing chest compressions on a patient is provided, said system comprising:

a chest compression device operable to compress the chest of a patient;

a battery for supplying power to the chest compression device;

a control system configured to control the chest compression device and write patient data and/or device data detected by sensors associated with the system to a storage device;

a battery retainer comprising a retaining structure for retaining the battery, configured to secure the battery to the chest compression device and operable by the user to release the battery from the chest compression device, wherein operation by the user to release the battery from the chest compression device requires moving the retaining structure through a range of motion, including an initial range of motion less than a full range of motion required to release the battery from the chest compression device; and

a sensor for detecting a motion of the retaining structure at a point in the range of motion prior to release of the battery, said sensor operable to generate a signal indicative of said motion and transmit said signal to the control system;

wherein the control system is operable to receive the signal indicative of said motion and programmed to cease writing patient data and/or device data to the storage device upon receiving the signal indicative of said motion.

The control system may be operable to perform the step of ceasing writing of patient data and/or device data to the storage device upon receiving the signal indicative of the motion, with a predetermined time period. The battery retainer may be further configured such that the time required for a user to move the retaining structure from the initial range of motion through the full range of motion

exceeds the predetermined time period. The step of ceasing writing of patient data and/or device data to the storage device may include (1) completing any writing in progress when the signal indicative of the motion is received, and (2) ceasing further writing of patient data and/or device data to the storage device. The battery retainer may comprise a battery cover. The retaining structure may comprise a first latch component interoperable with a second latch component in a housing of the chest compression device. The system may further comprise an actuator for translating the first latch component out of engagement with the second latch component. The sensor may be operable to detect motion of the actuator. The actuator may comprise a cam plate with a first lobe disposed on the cam plate. The first lobe may be located on the cam so as to impinge on the sensor when the cam is rotated through a first arc. There may be a second lobe disposed on the cam plate. The second lobe may be located on the cam so as to impinge on the first latch component such that rotation of the cam plate through a second arc results in the translation of the first latch component out of engagement with the second latch component. The actuator may be manually operable by the user. The first lobe and second lobe of the cam plate may be not co-planar. The sensor may be substantially co-planar with the first lobe. The first latch component may be substantially co-planar with second lobe of the cam plate. The first lobe may be disposed on the cam plate at a first radial position. The second lobe may be disposed on the cam plate at a second radial position. The second radial position may be radially displaced around the cam lobe from said first radial position. The chest compression device may further comprise one or more drive spools. A motor shaft may be operably connected to a drive spool for rotating the drive spool. The drive spool may be configured for attachment to a belt for compressing the chest of the patient.

According to another aspect, a system for performing chest compressions on a patient is provided, said system comprising:

a chest compression device operable to compress the chest of a patient;

a battery for supplying power to the chest compression device;

control system is configured to control the chest compression device and write patient data and/or device data detected by sensors associated with the system to a storage device;

a battery retainer comprising a retaining structure for retaining the battery, configured to secure the battery to the chest compression device and operable by a user to release the battery from the chest compression device;

a sensor for detecting a motion of the retaining structure at a point in the range of motion prior to release of the battery, said sensor operable to generate a signal indicative of said motion and transmit said signal to the control system;

wherein the control system is operable to receive the signal indicative of said motion and programmed to cease writing patient data and/or device data to the storage device upon receiving the signal indicative of said motion.

The control system may be operable to cease writing of patient data and/or device data to the storage device upon receiving the signal indicative of the motion, with a predetermined time period. The battery retainer may be further configured such that the time required for the user to move the retaining structure to electrically disconnect the battery from the chest compression device exceeds the predetermined time period. The step of ceasing writing of patient data and/or device data to the storage device may include (1)

completing any writing in progress when the signal indicative of the motion is received, and (2) ceasing further writing of patient data and/or device data to the storage device. The battery retainer may comprise a battery cover. The retaining structure may comprise a first latch component interoperable with a second latch component in a housing of the chest compression device. The system may further comprise an actuator for translating the first latch component out of engagement with the second latch component. The sensor may be operable to detect motion of the actuator. The actuator may comprise a cam plate with a first lobe disposed on the cam plate. The first lobe may be located on the cam so as to impinge on the sensor when the cam is rotated through a first arc. There may be a second lobe disposed on the cam plate. The second lobe may be located on the cam so as to impinge on the first latch component such that rotation of the cam plate through a second arc results in the translation of the first latch component out of engagement with the second latch component. The actuator may be manually operable by the user. The first lobe and second lobe of the cam plate may be not co-planar. The sensor may be substantially co-planar with the first lobe. The first latch component may be substantially co-planar with second lobe of the cam plate. The first lobe may be disposed on the cam plate at a first radial position. The second lobe may be disposed on the cam plate at a second radial position. The second radial position may be radially displaced around the cam lobe from said first radial position. The chest compression device may further comprise one or more drive spools. A motor shaft may be operably connected to a drive spool for rotating the drive spool. The drive spool may be configured for attachment to a belt for compressing the chest of the patient.

A filter may cover at least one of an intake aperture, compartment inlet aperture, and/or exhaust aperture. The filter may comprise a first layer; and a second layer. At least the second layer may be hydrophobic.

According to another aspect, a multi-layer filter is provided, the multi-layer filter comprising:

a filter covering at least one of an intake aperture, compartment inlet aperture, and/or exhaust aperture; wherein the filter comprises:

a first layer; and

a second layer, wherein at least the second layer is hydrophobic.

The first and second layers may comprise one or more openings. The first layer may be more rigid than the second layer. The first layer may comprise a metal mesh or perforated metal. The second layer may comprise a hydrophobic mesh air filter. The filter may further comprise a third layer.

The first and third layers may be mesh. The first layer may have a larger mesh size than the third layer. The filter may further comprise a third layer comprising a metal mesh. The filter may comprise a fourth layer comprising a hydrophobic mesh air filter. The filter may comprise a fifth layer comprising a metal mesh. The filter may comprise a sixth layer comprising a hydrophobic mesh air filter. The filter may comprise a seventh layer comprising a metal mesh. The first layer may be an outer mesh layer, and the mesh may have a first mesh size. The third layer may be intermediate the first layer and fifth or seventh layer, and the mesh of the third layer may have a second mesh size, where the first mesh size is larger than the first mesh size. The fifth or seventh layer may be an inner layer, and the metal mesh of the fifth or seventh layer may have a third mesh size, where the second mesh size is larger than the third mesh size. In certain embodiments, one or more of the multi-layer filters

60 have a first mesh size. The third layer may be intermediate the first layer and fifth or seventh layer, and the mesh of the third layer may have a second mesh size, where the first mesh size is larger than the first mesh size. The fifth or seventh layer may be an inner layer, and the metal mesh of the fifth or seventh layer may have a third mesh size, where the second mesh size is larger than the third mesh size. In certain embodiments, one or more of the multi-layer filters

11

described herein may cover one or more of the chest compression device apertures or openings described herein.

BRIEF DESCRIPTION OF THE DRAWINGS

FIG. 1 illustrates the CPR chest compression device installed on a patient.

FIG. 2 is a perspective view of the CPR chest compression device, illustrating the cooling intake baffles and outlet baffles within of the housing.

FIG. 3 is a perspective view of the CPR chest compression device, illustrating the apertures in the housing for cooling flow exhaust.

FIG. 4 is an anterior view of the CPR chest compression device, illustrating the cooling intake baffles and outlet baffles within of the housing.

FIGS. 5 and 6 illustrate an embodiment of the CPR chest compression device similar to that of FIGS. 2 and 4, with a different cooling flow path.

FIG. 7 illustrate an embodiment of a multi-layer filter for use with the CPR chest compression device.

FIG. 8 is a top/superior view of the CPR chest compression device, illustrating the cooling intake flow path between the housing baffles and the battery.

FIGS. 9 through 13 illustrate the operation of the battery disconnection detection mechanism which detects an attempt to remove the battery and saves various data upon detection during a short period required for an operator to complete actions required to remove the battery.

DETAILED DESCRIPTION

FIG. 1 shows a chest compression device fitted on a patient 1. The chest compression device 2 applies compressions with the compression belt 3. The chest compression device 2 includes a belt drive platform 4 sized for placement under the thorax of the patient, upon which the patient rests during use and which provides a housing 5 for the drive train and control system for the device. The control system, provided anywhere in the device, can include a processor and may be operable to control tightening or loosening operation of the belt and to provide output on a user interface disposed on the housing. Operation of the device can be initiated and adjusted by a user through a control panel 6 and/or a display operated by the control system to provide feedback regarding the status of the device to the user. The control system is configured to control the device to perform repeated compression cycles when the device is fitted about a patient's chest. A compression cycle includes a downstroke, an upstroke (a release portion), and perhaps some delay between a downstroke and a successive upstroke, or between an upstroke and a successive downstroke. In the operation of the AUTOPULSE® chest compression device, the system operates to take up slack in the belt upon initial start-up, equates the rotational position of the drive spool at this point as the slack take-up position, and begins each downstroke from this position.

The belt includes a wide load-distribution section 7 at the mid-portion of the belt and left and right belt ends 8R and 8L (shown in the illustration as narrow pull straps 9R and 9L), which serve as tensioning portions which extend from the load distributing portion, posteriorly relative to the patient, to drive spools within or on the housing. When fitted on a patient, the load distribution section is disposed over the anterior chest wall of the patient, and the left and right belt

12

ends extend posteriorly over the right and left axilla of the patient to connect to their respective lateral drive spools shown in FIG. 2.

FIGS. 2 and 3 shows the CPR chest compression device in isolation. FIG. 2 provides a view of the device with the housing anterior surface hidden. As illustrated in FIG. 2, drive spools 10R and 10L are disposed laterally on either side of the housing. The belt pulls straps 9R and 9L (shown in FIG. 1) are secured to these drive spools, locked into channels 11 running longitudinally along the drive spools. The lateral drive spools are in turn driven by a motor 12 also disposed within the housing, through a motor shaft 13, a transmission 14, a drive shaft 15 and drive belts 16R and 16L. The belt pull straps 9R and 9L are attached to the lateral drive spools such that, upon rotation of the drive spools, the pull straps 9R and 9L are pulled posteriorly, spooled upon the lateral spools, thereby drawing the compression belt downward to compress the chest of the patient.

Features of the ventilation system are also illustrated in FIG. 2. The motor 12 is disposed within a motor enclosure bounded by side walls 17R and 17L and an inferior wall 18, and a superior wall 19. An inlet to the motor compartment is provided by one or more motor compartment inlet apertures 20. (The motor compartment inlet aperture may be the same as the chest compression housing intake aperture 27.) An outlet for the motor enclosure is provided by an exhaust aperture 21. An exhaust fan 22, proximate the exhaust aperture, is operable to draw air from the motor enclosure and force it out of the motor enclosure through the exhaust aperture. The motor itself is characterized by a motor housing, a first end 23 and a second end 24, with the motor shaft 13 disposed at the second end, and a motor housing inlet aperture 25 in the motor housing proximate the first end, and a motor housing outlet aperture 26 in the motor housing proximate the second end.

The compression device housing is configured to support the patient during operation of the CPR compression device, and also forms an enclosure substantially enclosing the motor. The compression device housing has an intake aperture 27 for intake of cooling airflow and exhaust aperture 28 for exhaust of cooling airflow. An inlet aperture and an exhaust aperture may be provided on each side of the device.

The fan 22 is disposed within the compression device housing, proximate the second end of the motor housing and between the second end 24 of the motor housing and the exhaust aperture 28. The fan is arranged to draw air from the second end of the motor housing and force air out the exhaust aperture of the compression device housing. Alternatively, the fan can be reversed, to draw or force air into the second end of the motor and out of the first end of the motor, or draw air from aperture 28 and force air out of aperture 27. The fan and/or exhaust aperture may instead be disposed at the first end of the motor with an intake aperture proximate the second end of the motor housing, and may also be integral to the motor. One fan may be used on each side of the housing, as shown, or a single fan may be used. The control system may control the fan(s) to operate continuously, or intermittently as necessary to cool the device, independent of the operation of the motor.

Further referring to FIG. 2 and FIG. 4, to provide cooling flow to the battery, the compression device housing can be configured so as to place the battery in the cooling flow pathway. The battery 29 fits in a battery compartment 30 bounded by side walls 31R and 31L and an inferior wall 32, with an aperture 33 leading to the motor housing, and an intake aperture 34 formed in the superior surface 35 above the battery which allows for insertion and removal of the

battery. The superior intake aperture in this embodiment is in fluid communication with the housing intake aperture 27 identified above. (This superior aperture may be a gap between a battery cover and the compression device housing, as illustrated below, or a gap in the battery cover.) The battery is configured relative to the battery compartment so as to define a flow path for air from the intake aperture 34 of the compression device housing to the first aperture of the motor housing. The battery may be sized relative to the battery compartment so that the flow path is defined between a surface of the battery and an internal surface of the compression device housing, or the battery may be configured with a channel running through the battery, so that the channel defines the flow path.

The various walls and surfaces may be disposed within the compression device housing, between the intake aperture of the compression device housing and the first end of the motor housing, configured to serve as baffles to direct air drawn by the fan through the intake aperture of the compression device housing to the motor, including to the first aperture of the motor housing (with the configuration adjusted depending on whether the motor housing first aperture is also the intake aperture of the compression device housing, or the motor housing first aperture is downstream from the battery disposed between the motor and the intake aperture of the compression device housing. The intake aperture of the compression device housing may be located in the compression device housing such that it sits behind the battery (when the battery is inserted into the chest compression device), with a gap remaining between the intake aperture of the chest compression device and the battery cover, to allow for the flow/passage of air. This positioning of the compression device intake aperture helps protect or shield the compression device intake aperture from being blocked or obstructed, which could result in the overheating of or damage to the motor and compression device. The location of the intake aperture may be recessed relative to a posterior surface of the chest compression device housing.

Other walls that separate the battery compartment from the first end of the motor, disposed between the intake aperture of the compression device housing and the first motor end, having an aperture communicating from the battery compartment to the first end of the motor, define a second baffle within the compression device housing. The enclosure formed by the compression device housing is configured with internal surfaces to direct air drawn by the fan through the intake aperture of the chest compression device housing, to the first aperture in the motor housing (if they are distinct) and further configured with internal surfaces to direct air drawn by the fan from the second aperture in the motor housing, through the fan, and out the exhaust aperture. The battery compartment internal surface may also be configured to prevent air drawn by the fan through the intake aperture of the compression device housing from flowing through the battery compartment along pathways not at least partially defined by the battery configured for insertion into the battery compartment.

Various motors may be utilized, e.g., the motor may be a brushed DC motor, with a commutator and brush assembly disposed at the first end (opposite the motor shaft).

FIG. 3 is a perspective view of the CPR chest compression device, illustrating the apertures in the compression device housing which provide for access to the drive spool for connecting the belt to the drive spool. The apertures 36R and 36L on either side of the housing are disposed proximate the drive spools. The apertures are sized to allow passage of

the belt end through the housing wall for insertion into the drive spools. The apertures can extend over the housing anterior surface 5A and lateral surface 5L as shown, or over the housing anterior surface 5A alone, or the lateral surface 5L alone, to preferably provide access to the drive spools from an anterior approach or lateral approach even while a patient is disposed on the anterior surface. Spindles 37R and 37L may be provided to guide the belt ends through the apertures.

FIG. 3 also illustrates the position of the exhaust apertures 28 of the housing, which, in this embodiment, are distinct from the apertures used to access the drive spools. The drive spool apertures are isolated from the ventilation flow by the inferior wall 18 of the motor compartment.

FIG. 4 is an anterior view of the CPR chest compression device, illustrating the cooling intake baffles and outlet baffles within of the housing. This figure more clearly shows the location of the motor enclosure side walls 17R and 17L, inferior wall 18, superior wall 19, motor compartment inlet aperture 20 and motor compartment exhaust aperture 21. Portions of the motor include the motor first end, motor second end, and the motor housing inlet aperture 25 in the motor housing proximate the first end, and a motor housing outlet aperture 26. The compression device intake aperture 27 and exhaust aperture 28, and the fan 22 are also shown. The walls 31R, 31L and 32 of the battery compartment 30 are also shown in this view.

FIGS. 5 and 6 illustrate an embodiment of the CPR chest compression device similar to that of FIGS. 2 and 4, with a different cooling flow path. FIG. 5 shows a view of the device with the housing anterior surface hidden. As in FIG. 2, drive spools 10R and 10L are disposed laterally on either side of the housing. The belt pulls straps 9R and 9L (shown in FIG. 1) are secured to these drive spools, locked into channels 11 running longitudinally along the drive spools. The lateral drive spools are in turn driven by a motor 12 also disposed within the housing, through a motor shaft 13, a gearbox or transmission 14, a drive shaft 15 and drive belts 16R and 16L. The belt pull straps 9R and 9L are attached to the lateral drive spools such that, upon rotation of the drive spools, the pull straps 9R and 9L are pulled posteriorly, spooled upon the lateral spools, thereby drawing the compression belt downward to compress the chest of the patient.

Features of the alternative ventilation system are also illustrated in FIGS. 5 and 6. The ventilation system provides for lateral intake of cooling air flow from one side of the chest compression device housing, and lateral exhaust of cooling air flow from the opposite side of the chest compression device housing, while providing axial flow of cooling air through the motor housing. The motor 12 is disposed within a motor enclosure or compartment bounded by side walls 17R and 17L and an inferior wall 18, and a superior wall 19. An intake aperture to the compression device housing, which also serves as the inlet to the motor compartment, is provided by one of the lateral openings 28R or 28L, with its associated fan 22R or 22L operable as an intake fan, to draw air into the housing and motor enclosure or compartment. (The arrows used to depict airflow in this figure are based on intake on the right and exhaust on the left side of the CPR chest compression device) In other embodiments, airflow may include intake on the left and exhaust on the right side of the chest compression device. The inlet for the motor enclosure is provided at a location lateral to the motor, such as motor enclosure aperture 21L (or 21L) (shown in FIG. 6), and airflow is directed superiorly past the motor housing (arrow 39), and is forced or drawn inferiorly through the motor housing, entering though the motor hous-

ing inlet aperture 25, flowing axially, and inferiorly, through the motor housing, and exiting through a motor housing outlet aperture 26. The motor housing may optionally have an outlet aperture 26 only on the exhaust side of the system. Cooling air flow then exits the motor enclosure through a lateral exhaust aperture on the opposite side of the motor enclosure from the inlet aperture. The fan (22L or 22R) opposite the fan serving as an intake fan serves as an exhaust fan, drawing cooling flow from the motor enclosure and directing it out of the motor enclosure and out through chest compression housing exhaust aperture 28L or 28R (the aperture opposite the intake aperture). An outlet for the motor enclosure is provided by an exhaust aperture 21R or 21L (the motor enclosure aperture opposite the motor enclosure inlet). The exhaust fan, proximate the exhaust aperture, is operable to draw air from the motor enclosure and force it out of the motor enclosure through the exhaust aperture. The motor itself is characterized by a motor housing, a first end 23 and a second end 24, with the motor shaft 13 disposed at the second end, and a motor housing inlet aperture 25 in the motor housing proximate the first end, and a motor housing outlet aperture 26 in the motor housing proximate the second end. In this embodiment, the openings in the motor enclosure are modified, vis-à-vis those of FIGS. 2 and 4, to promote axial flow of air through the motor housing and prevent escape of cooling air flow through, for example, the battery compartment. The motor enclosure superior wall 19 is substantially solid (or the battery compartment is substantially sealed), lacking the apertures 20 shown in FIGS. 2 and 4, so that no significant airflow can pass out of the superior boundary of the motor enclosure. Also, airflow over the motor housing, as opposed to airflow through the motor housing, on the side opposite the intake, is blocked by baffle 40 or wall, on the exhaust side of the system, and no corresponding baffle is provided on the intake side of the system, to allow cooling air flow to pass superiorly to the motor housing inlet aperture. Cross-flow through the motor second end is prevented, as the aperture 24 is provided only on the exhaust side of the system, and the motor housing, at the motor second end, is substantially sealed against cooling air flow entering directly from the intake fan. The compression device housing is configured with additional baffles or walls blocking lateral air flow around the motor, or the motor housing is sealed against interior surfaces of the lower housing component and the upper housing component, to prevent laterally directed flow over the motor housing, which would bypass the axial flow path through the motor housing. Though it is effective to use two fans, with one serving as an intake fan and one serving as an exhaust fan, the system may use a single fan, serving either as an intake fan (to force air into the system on one side) or as an exhaust fan (to pull air out of the system on one side). In certain embodiments, the above described airflow path may be reversed, by swapping the position of the exhaust fan and/or intake fan.

FIG. 6 is an anterior view of the CPR chest compression device of FIG. 5, illustrating the cooling intake baffles or walls and outlet baffles or walls within of the housing. This figure more clearly shows the location of the motor enclosure side walls 17R and 17L, inferior wall 18, and superior wall 19, the flow-path (arrow 39) leading from the lateral motor enclosure inlet aperture 21L, in this example, to the motor first end 23 and motor housing intake aperture 25, and the baffle 40 proximate the motor housing that inhibits bypass flow over the motor housing. Portions of the motor include the motor first end, motor second end, and the motor housing inlet aperture 25 in the motor housing proximate the

first end, and a motor housing outlet aperture 26 proximate the motor second end. The compression device intake aperture 27 of FIGS. 2 and 4 is not used for air flow in this embodiment, allowing for a more secure liquid-tight seal of the battery compartment.

In the embodiment of FIGS. 5 and 6, cooling flow can also be provided to the gearbox or transmission 14 by providing apertures 41R and 41L in the motor enclosure inferior wall 18, on opposite sides of the gearbox or transmission, such that some cooling flow will bypass the motor cooling flow (arrow 39) and flow through a first aperture 41R or 41L in motor enclosure inferior wall 18, over the gear box, and out the second aperture 41R or 41L. The apertures may be sized to control the distribution of airflow between the motor and the gear box. For example, the apertures may be sized to allow for greater airflow to the gearbox or transmission than to the motor (e.g., in a ratio 80(gearbox)/20(motor)). In another example, the apertures may be sized to allow for equal airflow between the motor and gearbox or transmission. Optional additional baffles 42 can be provided on either side of the gearbox or transmission 14 to constrain cooling flow over the gearbox or transmission 14.

FIG. 5 also illustrates a variant of the bottom half of the CPR chest compression device housing 5. In this embodiment, bosses 43A and 43B may be used to provide structural strength to the entire housing, facilitate alignment during assembly, and secure the upper half of the CPR chest compression device housing to the bottom. The bosses in this embodiment are conical, with a base (the point of attachment to the housing) being wider than the end of the boss. The conical shape allows for improved flow of material (e.g., plastic) during manufacturing, such that the conical boss can have a wall thickness equal to or greater than the thickness of the chest compression device housing from which the boss extends. The bosses may include pilot holes configured to accept screws driven through corresponding apertures in the bottom half of the CPR chest compression device housing, but bosses in an area that might be subject to imaging (X-ray, MRI, etc.), (bosses 43B) which would correspond to the location of the patient's heart when the device is installed on a patient, may be provided with snap-fit or friction fit features configured to mate with corresponding receiving features in the bottom half of the CPR chest compression device housing (or vice-versa).

One or more of the several apertures, including the compression device housing intake aperture 27, the compression device housing exhaust aperture 28, and the motor compartment inlet aperture 20 or the motor compartment exhaust aperture 21, may be covered with a hydrophobic mesh. The hydrophobic mesh may be a single layer or have a plurality of layers.

In one example, to provide a more effective barrier against the entry of fluids, the several apertures can be covered with a multi-layer filter. For example, the filter may include layers with one or more openings, wherein one layer may be more or less rigid than another layer. The filter may include two or more layers, e.g., a layer including a perforated layer/material or mesh made from metal (e.g., wire cloth) or other rigid material (e.g., plastic), and a layer including a hydrophobic mesh air filter. The metal or other rigid material mesh or perforated layer may serve as the outer layer (for aesthetics and cleanability) and/or as an intermediate layer or spacer between two less rigid hydrophobic mesh air filter layers to provide structural support to those layers. The metal or other rigid material mesh or perforated layer may also be positioned relative to the hydrophobic mesh air filter such that the openings or pores in the mesh or perforated

layer are offset relative to the openings or pores in the hydrophobic mesh air filter to diffuse or reduce the energy of fluid passing therethrough. The various layers of mesh or perforated material may have different or the same mesh or opening sizes. For example, where two or more layers of metal (or other rigid material) mesh are used, the two layers may have different mesh sizes. Where two or more hydrophobic mesh air filter layers are utilized, the layers may have different or equal mesh sizes.

In one example of a filter embodiment, illustrated in FIG. 7, the filter may include the following layers:

- 1) an external layer of metal wire cloth (item 44 in FIG. 7) (for example, a stainless steel mesh having a first mesh size of 38×38, with 0.508 mm (0.02") openings and 0.165 mm (0.0065") wire diameter (providing an open area of 57%);
- 2) a hydrophobic mesh air filter (item 45) (with, for example, a 38% open area, openings of 125 microns, 2.9 warp fibers per mm (125 warp fibers per inch) and 2.9 weft fibers per mm (125 warp fibers per inch);
- 3) a layer of metal wire cloth (item 46) (for example, a stainless steel mesh having a second mesh size of 15×15, with 1.4478 mm (0.057") openings and 0.254 mm (0.01") wire diameter (providing an open area of 73%);
- 4) a hydrophobic mesh air filter (item 47) (with, for example, a 38% open area, openings of 125 microns, 2.9 warp fibers per mm (125 warp fibers per inch) and 2.9 weft fibers per mm (125 warp fibers per inch);
- 5) a layer of metal wire cloth (item 48) (for example, a stainless steel mesh having a third mesh size of 15×15, with 1.4478 mm (0.057") openings and 0.254 mm (0.01") wire diameter (providing an open area of 73%);
- 6) a hydrophobic mesh air filter (item 49) (with, for example, a 38% open area, openings of 125 microns, 2.9 warp fibers per mm (125 warp fibers per inch) and 2.9 weft fibers per mm (125 warp fibers per inch);
- 7) a layer of metal wire cloth (item 50) (for example, a stainless steel having a fourth mesh size of 4×4, with 5.6388 mm (0.222") openings and 0.7112 mm (0.028") wire diameter (providing an open area of 78%).

Thus, the filter may include several layers of metal mesh, and the seventh (or last) layer is an inner layer, wherein the first layer is an outer lay, with intervening layers of hydrophobic mesh. The filter can comprise a first layer comprising a metal mesh, a second layer comprising a hydrophobic mesh air filter; a third layer comprising a metal mesh; a fourth layer comprising a hydrophobic mesh air filter; a fifth layer comprising a metal mesh; a sixth layer comprising a hydrophobic mesh air filter; and a seventh layer comprising a metal mesh. The air filter layers may comprise meshes of similar specifications, and the metal mesh/cloth layers may comprise metal meshes of first mesh size in an outer layer, and a second mesh size in the intermediate layers and a third mesh size in the innermost layer, wherein the first mesh size is higher than the second mesh size, and the second mesh size is larger than the third mesh size.

Each embodiment of the chest compression may incorporate a filter as described above to cover one or more intake, inlet or exhaust apertures.

FIG. 8 is a top/superior view of the CPR chest compression device of FIG. 2, illustrating the cooling intake flow path between the compression device housing baffles and the battery. This view shows the battery 29 within the battery compartment 30, bounded by the side walls 31R and 31L.

The small gaps 38 between the battery and the walls of the battery compartment provide a flow path for cooling air over the battery.

Though the features provided for providing cooling air-flow to heat generating components of the CPR chest compression device have been described in the context of belt-driven CPR chest compression devices, they may be incorporated into other CP chest compression devices, such as piston-based compression devices and hybrid systems using both piston actuators and compression belts.

A CPR chest compression device can include a mechanism for detecting an attempt to remove its battery, and placing the control system in a safe condition, including completing the writing of collected patient and/or device data to a storage device, and ceasing further writing, before the battery is removed, or electrically disconnected by a user. In a system where the control system is configured to control the chest compression device and write patient data and/or device data detected by sensors associated with the system to a storage device, a battery retainer may be configured to provide a signal to the control system indicating an attempt to remove the battery, and the control system can be correspondingly programmed to receive the signal and save data and cease writing data within a predetermined period which is shorter than the time required to complete battery removal or move the battery sufficient to electrically disconnect the battery from the compression device. This system comprises a retaining structure, e.g., mechanical, for retaining the battery, configured to secure the battery to the chest compression device. The battery retainer may be automated or manually operable by the user to release the battery from the chest compression device. In certain embodiments operation by the user to release the battery from the chest compression device may require moving a mechanical retaining structure through a range of motion, including an initial range of motion less than a full range of motion required to release the battery from the chest compression device. A sensor for detecting a motion of the retaining structure at a point in the range of motion prior to release of the battery (an initial range of motion), and the sensor operable to generate a signal indicative of said motion and transmit said signal to the control system. The control system is operable to receive the signal indicative of the motion and is programmed to cease writing patient data and/or device data to the storage device upon receiving the signal indicative of said motion. The control system may be operable to (1) complete any writing in progress when the signal indicative of the motion is received, and (2) cease further writing of patient data and/or device data to the media upon receiving the signal indicative of the motion, within the predetermined time period. The battery retainer may be further configured such that the time required for a user to move the retaining structure from the initial range of motion through the full range of motion exceeds the predetermined time period. In certain embodiments, the CPR chest compression device may be one or more of the compression devices described herein.

FIGS. 9 through 13 illustrate the operation of such a battery disconnection detection mechanism which detects an attempt to remove the battery and saves various data upon detection during a short period required for an operator to complete actions required to remove the battery. The chest compression device includes a control system operable to control operation of the chest compression device to perform repeated compression cycles when the device is fitted about a patient's chest, and also to collect patient data and/or device data (such as the operating start times and stop times,

battery life, compression rates, compression depths, total compressions applied and compressions pauses used, and other quality metrics) detected by sensors associated with the system to a storage device. In such a device, it would be advantageous to detect an attempt to remove the battery and, in response to this detection, operate the control system to save collected data to the storage device and cease writing to the storage device, and optionally inhibit the removal of the battery until the control system has completed these tasks.

FIG. 9 is a superior view of the CPR chest compression device 2 showing a battery cover 51 which covers and retains the battery in the battery compartment. The cover is shown in isolation in FIGS. 9 through 13. The battery cover includes battery retainer components interoperable with battery retainer components, in the housing. The battery retainer components may include a fastener, latch, clip, clamp or other fastening or latching connection mechanism. The battery cover may further include an operating mechanism (e.g., manual or automated) configured to detect an action required for battery removal, generate a signal corresponding to detection of the action required for removal and transmit this signal to the control system, and require a further action to remove the battery. The further action may require a period of time, between initiation and completion, sufficient for the control system to save data generated by other components of the system to a storage device, such that the data is saved to the storage device before the battery is removed. The battery cover shown in FIGS. 9 through 13 is an example of such a system. The components of the battery cover can be applied directly to the battery, or the battery cover can be fixed to the battery, or, as illustrated, the battery cover can be provided as a discrete component separate from the battery. As shown in FIG. 9, the cover includes a manually-operated actuator 52, operable by the operator to force a cam plate to rotate, and thus force the battery retainer component, which is a latch component in this example, downwardly (posteriorly, in relation to a patient to which the CPR compression device is attached). As shown in FIG. 10, the cover includes one or more latch components 53 which are configured to engage with corresponding latch components in the housing 5. The latch components are biased toward an engaging position by springs 54 or other biasing mechanism. A cam plate 55 with a first cam lobe 56 which is located on the cam so as to impinge on a contact switch 57 when rotated through a first arc.

The cam plate may include a second cam lobe 58, not co-planar with the first cam lobe 56, near a follower 59 fixed to the latch component 53, such that rotation of the cam plate (through a second arc, greater than the first arc) results in impingement of the lobe on the follower, and thus forces the latch component to move away from the center of the cam plate, and thus, in the illustrated configuration, downwardly against the force of the springs and out of engagement with the latch component(s) on the housing. The first cam lobe 56 acts on the contact switch 57 at a first radial position on the cam plate, and the second cam lobe 58 acts on the latch mechanism follower 59 (or directly on the latch mechanism) at a second radial position on the cam plate. The sensor is substantially co-planar with the first cam lobe and the first latch component (the latch component 53 or its associated follower 59) is substantially co-planar with second lobe of the cam plate. The first radial position is displaced (advanced) around the cam lobe, in the direction of rotation of the cam plate, relative to the second position, such that the first cam lobe makes contact with the contact switch before

the second cam lobe forces the cam follower downwardly to the extent necessary to force the latch component downwardly and out of engagement with the latch components on the housing. The control system of the device is operable to detect contact between the first cam lobe and the contact switch, and it is programmed such that, upon detection of contact between the first cam lobe and the contact switch, the control system will operate to save any patient data and/or device data collected by sensors associated with the system to storage device. This can be accomplished by the control system in a short period of time, before an operator can further rotate the actuator to the extent necessary to bring the second cam lobe into impingement with the cam follower to the extent necessary to force the latch component downwardly and out of engagement with the latch components on the housing.

When the battery is locked into the housing, the cam plate is positioned relative to the contact switch and follower as shown in FIG. 11, where the first cam lobe is arcuately displaced from the contact switch, and the second cam lobe is arcuately displaced from the follower. As shown in FIG. 12, when the operator rotates the cam plate through a first arc, the first cam lobe is arcuately aligned with the contact switch, while the second cam lobe is still arcuately displaced from the follower, so that the contact switch is actuated but the latch components are not moved. As shown in FIG. 13, upon further rotation of the cam plate, the second cam lobe rotates into alignment with the follower to force the follower and latch component downwardly.

The battery removal detection mechanism and sensor can be implemented in many ways. The contact switch is just one of many means or mechanisms for detecting operator action preceding battery removal. Other such means or mechanisms can include any form of contact or proximity sensor operable to sense proximity of the cam lobe with the sensing component, or any inductive sensor operable to detect operator contact with the actuator or any inductive sensor operable to detect motion of the actuator, including contact switches, contact relays, magnetic sensors, capacitive sensors inductive sensors, optical sensors, photocells, ultrasonic sensor, or any other means for sensing movement of the actuator. Sensors may include a first sensor component and second sensor component, e.g., a sensor target and a sensing component operable to sense the movement of the sensor target, and either sensor component may be disposed on the actuator or on the battery cover (or elsewhere on the device). A relay switch may comprise an electromagnetic switch operated by a small electric current, with a magnet or electromagnet on one structure (the cam or the cover) and a spring-loaded switch on the other structure, where proximity of the magnet or electromagnet functions to close or open the spring-loaded switch. A change in the switch position may be taken by the control system as a signal indicative of movement of the actuator. A contact switch may comprise a switch on one structure (the cam or the cover) activated by contact with an impinging component on other structure. For example, a reed switch disposed on the cover, operable to be closed by a protrusion on a cam lobe, when the cam is rotated. Closure of the switch may be taken by the control system as a signal indicative of movement of the actuator. A magnetic sensor may comprise a Hall effect sensor on one structure (the cam or the cover), and a magnet on the other structure. Detection of the magnetic field of the magnet may be taken by the control system as a signal indicative of movement of the actuator. A capacitive sensor may comprise a capacitive sensor probe with a sensing electrode on one structure (the cam or the cover), and a conductive target, or

a capacitive sensor probe on one structure, combined with a conductive target on the same structure on the opposite side of a channel which accommodates the other structure, operable to sense the entry of other structure (whether conductive or non-conductive) by its effect on the capacitance measured by the capacitive sensor probe. Detection of the target may be taken by the control system as a signal indicative of movement of the actuator. An inductive sensor may comprise a magnetic field oscillator on one structure (the cam or the cover), and a conductive target on the other structure. Detection of a change in the amplitude of the oscillator may be taken by the control system as a signal indicative of movement of the actuator. An optical sensor may comprise photoelectric detectors and optical encoders. Optical encoders, for example, may comprise an encoder scanner on one structure (the actuator or the cover), and an encoder scale on the other structure. Detection of the encoder scale by the encoder scanner may be taken by the control system as a signal indicative of movement of the actuator. A photoelectric sensor may comprise an emitter light source on one structure (the actuator or the cover), and a photodetector on the other structure (or a reflector on the other structure and a photodetector on the first structure). Detection of light, or loss of detection of light, from the emitter light source by the photodetector may be taken by the control system as a signal indicative of movement of the actuator. An ultrasound sensor may comprise a transducer on one structure (the actuator or the cover), and a reflective target on the other structure (the structure itself may constitute the target), in a through-beam or reflective arrangement. Detection of light reflected by the target, or alteration of the light by transmission through the target may be taken by the control system as a signal indicative of movement of the actuator.

The battery retainer components may take many forms as well. The latch component for engaging the housing is just one of many latching or fastening mechanisms for securing the battery cover to the housing. Other such mechanisms can include any form of latching or fastening mechanism, including clamps, clips or restraints, a compression latch (pinching actuation), a push button, or pull-out feature mechanism, manually operated or automatically operated by the control system upon input from the user.

The battery cover is just one example of a battery retainer or battery hold-down that may be configured to hold the battery physically in place relative to the housing and in electrical communication with the control system and motor of the chest compression device. Many retaining structures may be used to lock the battery in place, without also serving to cover the battery and protect it from the environment outside the battery compartment. The retainer may comprise a toggle switch or clamp, a rotatable catch fixed to the battery or chest compression device, a drawer lock fixed to the battery or chest compression device, a rotatable threaded lid, a detent pin or ball locking pin.

Various patient and/or device data may be collected by the battery and/or chest compression device as discussed herein. Such data may be recorded and/or transmitted to a remote server or device, allowing for remote management of device or patient data. Exemplary data includes device performance data, such as compression fraction (the amount of time compressions were delivered during a CPR event); compression rate; compression depth; the frequency with which the device met a target depth; device self-test results; fault codes; battery performance; and predictive failure codes or check engine light codes (e.g., battery life or faulting).

Device and battery data may be transmitted in the following ways: Data from the compression device may be transmitted to the battery. The battery may be placed in a charger and data may be transferred from the battery (or the compression device) to the cloud or remote server. A user/manager may log in to their account via the internet to retrieve their device or battery data, e.g., to review their device performance and device data and/or to remotely manage or monitor their devices/assets. A user/manager may monitor chest compression device usage, battery life, etc. Alternatively, a user/manager may retrieve data directly via a USB port or other port present on the device or charger. Data may be transmitted to the cloud or remote server from the battery while the battery is charging.

While the preferred embodiments of the devices and methods have been described in reference to the environment in which they were developed, they are merely illustrative of the principles of the inventions. The elements of the various embodiments may be incorporated into each of the other species to obtain the benefits of those elements in combination with such other species, and the various beneficial features may be employed in embodiments alone or in combination with each other. Other embodiments and configurations may be devised without departing from the spirit of the inventions and the scope of the appended claims.

We claim:

1. A system for performing chest compressions on a patient, said system comprising:

a motor having a motor shaft, a first end, a second end, a first aperture proximate the first end, and a second aperture proximate the second end;

a transmission proximate the motor and operatively coupled to the motor;

a compression device housing for housing the motor, said compression device housing configured to support the patient during operation of the system, said compression device housing forming an enclosure substantially enclosing the motor and having an intake aperture for intake of cooling airflow and an exhaust aperture for exhaust of cooling airflow; and

a fan disposed within the compression device housing, said fan disposed proximate the motor between the motor and one of the intake aperture or the exhaust aperture of the compression device housing,

wherein the fan is arranged to draw or force air through the motor and/or draw or force air out the exhaust aperture of the compression device housing;

wherein the intake aperture is disposed in a lateral portion of the compression device housing on a first lateral side of the compression device housing,

wherein the exhaust aperture is disposed in a lateral portion of the compression device housing on a second lateral side of the compression device housing, and

wherein the compression device housing is configured with one or more baffles or walls to direct air, driven or drawn by the fan, into the first aperture in the motor proximate the first end of the motor, whereby air flows from the first lateral side of the compression device housing to the second lateral side of the compression device housing through the motor, the one or more baffles or walls configured to direct air in at least two flow paths in opposing directions to direct air towards the motor and the transmission, respectively.

2. The system of claim 1, further comprising:
a drive spool, wherein said motor shaft is operably connected to the drive spool for rotating the drive

23

- spool, said drive spool configured for attachment to a belt for compressing the chest of the patient.
3. The system of claim 1, wherein:
the fan is operable as an intake fan to force air through the motor; and
the system further comprises a second fan operable as an exhaust fan to draw air from the motor or from the compression device housing through the motor, and force air from the motor or from the compression device housing and out the exhaust aperture of the compression device housing.
4. The system of claim 1, wherein:
the one or more baffles or walls comprise one more apertures which are sized to allow for equal or different airflow between the motor and the transmission.
5. The system of claim 1, wherein:
the compression device housing further comprises seals or baffles to prevent or inhibit air flow from bypassing a flow path through the motor.
6. The system of claim 1, wherein:
the enclosure formed by the compression device housing is configured with internal surfaces to direct air drawn by the fan through the intake aperture to the first aperture in the motor.
7. The system of claim 1, wherein:
the enclosure formed by the compression device housing is further configured with internal surfaces to direct air drawn by the fan from the second aperture in the motor, through the fan, and out the exhaust aperture.
8. The system of claim 1, wherein:
the compression device housing is further configured with a battery compartment configured to hold a battery for powering the motor,
said battery compartment disposed in between the intake aperture and the first end of the motor,

24

- said battery compartment having an internal surface configured to direct air drawn by the fan through the intake aperture over or through the battery.
9. The system of claim 8, wherein:
the internal surface of the battery compartment is further configured to prevent air drawn by the fan through the intake aperture from flowing through the battery compartment along pathways not at least partially defined by a battery configured for insertion into the battery compartment.
10. The system of claim 8, further comprising:
a baffle within the compression device housing,
said baffle separating the battery compartment from the first end of the motor, said baffle also disposed between the intake aperture of the compression device housing and the first end of the motor,
said baffle having an aperture communicating from the battery compartment to the first end of the motor.
11. The system of claim 10, further comprising:
a hydrophobic mesh covering the aperture of the baffle.
12. The system of claim 1, wherein:
the motor is a brushed DC motor, the motor comprising a commutator and a brush assembly disposed proximate the first end.
13. The system of claim 1, further comprising:
a hydrophobic mesh covering the exhaust aperture.
14. The system of claim 1, further comprising:
a hydrophobic mesh covering the intake aperture.
15. The system of claim 1, wherein:
the intake aperture is in a location in the compression device housing that shields the intake aperture from being blocked or obstructed.
16. The system of claim 15, wherein:
the location of the intake aperture is recessed relative to a posterior surface of the compression device housing.
